PRESSURE FLUID MOTOR

Ernest H. Shaff, Grand Haven, Mich., assignor
to William H. Keller, Inc., Grand Haven, Mich.,
a corporation of Michigan

Application October 23, 1937, Serial No. 171,519

7 Claims. (Cl. 121—34)

The invention relates to motors adapted for actuation by pressure fluid for driving such tools as portable screw drivers, and more particularly to motors of the type embodying an eccentric relation in a cylinder of a rotor having generally radially movable vanes traversing the space between the rotor and cylinder to receive the driving force of the pressure fluid.

A general object of the invention is to provide a novel motor of this nature having improved features of construction enabling reversible operation with high efficiency.

Another object is to provide a new and improved motor having high operating efficiency which embodies an eccentric relation of a rotor carrying generally radially movable vanes in a cylinder bore of elliptical cross section, as distinguished from a circular section, the rotor being located in close proximity to the bore wall substantially on the minor axis of the ellipse and the dimensions and shape of the ellipse being such as to produce an outward movement of the vanes to an effective position for substantially maximum power derivation during a minimum rotational movement of the rotor.

Another object is to provide a new and improved reversible motor of the character set forth including a novel arrangement of pressure fluid inlet and exhaust ports and a simple valve arrangement controlling the flow of motive fluid.

In conjunction with the foregoing, another object stated more specifically is to provide, in a motor having highly efficient operating characteristics resulting from the coordination of a vaned rotor and an elliptically shaped cylinder bore, an exhaust port which is constantly open to atmosphere and is common to a pair of pressure fluid ports capable of being connected selectively with a source of pressure fluid by a simple reversing valve mechanism to effect movement of the rotor in one direction or the other.

Further objects reside in the provision of various features of construction and element relationships including means for positively extending the vanes into cylinder wall engagement by pressure fluid and a simplified arrangement of passageways for the flow of pressure fluid through the motor.

Other objects and advantages will become apparent in the following description and from the accompanying drawing, in which:

Figure 1 is a longitudinal axial section through a tool and motor embodying the features of the invention.

Figs. 2 and 3 are transverse sectional views

taken substantially on the lines 2—2 and 3—3 respectively of Fig. 1 and looking in the direction of the arrows.

Fig. 4 is a rear elevation of the tool shown in Fig. 1.

Fig. 5 is a view in perspective of the motor cylinder.

Fig. 6 is an expanded view showing the parts of the valve assembly in perspective.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

An important feature of the present invention is the relationship of parts by which a simple, yet highly efficient reversible pressure fluid actuated motor is obtained. As far as I am aware, it has heretofore been the practice in motors of this nature to mount a cylindrical vane carrying rotor eccentrically in a cylindrical bore. High efficiency in such a motor could only be obtained by subjecting the vanes to the force of pressure fluid throughout the major portion of a revolution, for example some two-thirds of a revolution, the exhaust of expended pressure fluid taking place through the remaining one-third of the movement. To make such a motor reversible necessitated the provision of separate exhaust ports controlled by separate valve mechanisms with the result that the motor was complicated and expensive.

According to the present invention, a cylindrical rotor is journaled for movement in a cylinder having a bore of generally elliptical cross section, the rotor being mounted eccentrically in the bore with one side of the rotor in close proximity to the wall of the bore. The point of the smallest dimension of the space between the rotor and the cylinder is preferably located approximately on the plane of the minor axis of the ellipse. This point of smallest space dimension may, for convenience, be termed the point or line of running contact between the rotor and bore wall, although it is not essential that the rotor and the cylinder be actually in contact.

The dimensions and shape of the ellipse, and with particular reference to the curvature of the bore wall on either side of the line of running contact, is preferably determined by a balance be-

tween two factors. For high efficiency, it is desirable that the rotor vanes be projected to their full working extent within the shortest possible distance of rotative movement of the rotor. Since in a reversible motor the fully projected vanes are forced inwardly of the rotor by the engagement thereof with the same portion of the bore wall which permits their outward movement, it is necessary that the slope of the bore wall be sufficiently gradual or slow to move the vanes inwardly of the rotor smoothly and without binding. A balance of these two conditions will produce a motor having a high operating efficiency.

In the present embodiment of the invention, the ellipse is shown as being in the form of a flattened circle. In this form, the vanes will be projected substantially to their most efficient working position during approximately the first third of a revolution, the position being determined approximately by the major axis of the ellipse. This full projection of the vanes will, in a reversible motor, occur during the same distance of travel of a vane in either direction from the point of running contact. Through the distance between the points at which the vanes reach their fully extended position, at which points the dimension of the space between the rotor and cylinder is approximately at its greatest, the somewhat flattened circle form of ellipse provides a space which does not materially vary from that greatest dimension. The power derived by the vanes from the pressure fluid may, therefore, be almost completely transmitted to the rotor during approximately a half-revolution of the rotor. Without a loss of efficiency, therefore, an exhaust port which is permanently open to atmosphere, may be located at a point substantially diametrically opposed to the line of running contact. This exhaust port permits escape of expended pressure fluid from the space between the rotor and cylinder regardless of the direction of movement of the rotor and may, therefore, be said to be common to both of the pressure fluid inlets.

Merely for illustrative purposes, the present invention has been shown as the prime moving element in a tool such as a portable screw driver. It is to be understood, however, that the invention may be readily used in other environments. Referring particularly to Fig. 1, the tool structure in its present embodiment comprises a sectional casing including a rear section 10, fashioned as a pistol grip for the convenience of the operator, an intermediate cylindrical section 11 forming the motor housing, and a front section 12 within which driving gears 13 and a tool spindle 14 are mounted. The casing sections are preferably detachably connected by screw threaded unions 15.

The motor, which for the most part is housed within the casing section 11, comprises a cylinder 16 (Figs. 1 and 2) and rotor 17. The cylinder is elongated and has a bore 18 therein which is of elliptical cross section. The rotor is an elongated cylinder fixed as by a key 19 to a shaft 20 dimensioned to extend through and beyond each end of the rotor and cylinder. Its rear end is carried by a bearing 21 seated in a suitable recess 22 formed in the front end face of the rear casing section 10. The other end of the shaft is journaled in a similar bearing 23 mounted within a circular flange 24 preferably formed as an integral part of an end plate 25 which abuts and closes the front end of the cylinder 16. The end

plate 25 may be secured in place by such an arrangement as annular spacing means 26 interposed between the plate and a ring gear 28 fixed in the front casing section 12 for binding the front plate 25 against the cylinder end when the casing sections 11 and 12 are secured together. The other end of the cylinder may be closed by a rear end plate 27 interposed between the end of the cylinder and the front face of the rear casing section 10. Pins 28, or the like, extending between the front end plate 25 and the cylinder 16, and from the cylinder through the rear end plate 27 into the rear casing section 10, may be employed to hold the parts against axial rotation or displacement.

The location of the rotor within the elliptical bore 18 is such that the axis of rotation of the rotor is located approximately on the plane of the shorter or minor axis of the bore, and is eccentric with respect to the center of the bore to dispose one side of the rotor in close proximity to the bore wall. Preferably the rotor is substantially in running contact with the cylinder and the line of the smallest space dimension between the rotor and cylinder, is located approximately on the minor axis of the elliptical bore.

The rotor is provided with a series of radially extending peripherally opening slots 30 (Fig. 2) which are preferably equidistantly spaced in a circumferential direction. Each slot slidably supports a flat member or vane 31 for radial projection into engagement with the opposed surface of the bore wall. In the present embodiment of the invention, it has been found that maximum efficiency of the motor is derived when six such vanes are used. During rotation, the vanes will follow the contour of the bore, an outward projection of the vanes being obtained as the result of centrifugal force acting thereon or by other means as will hereinafter be more particularly described. The driven movement of the rotor results from subjecting the portions of the vanes extending beyond the rotor to the force of a suitable pressure fluid, such as compressed air.

The wall of the cylinder along the so-called line of running contact is substantially thickened, as indicated at 32. Preferably, the pins 28 extend into the thickened portion of the cylinder substantially on the plane of said line. On each side of the plane of said line, the thickened portion of the cylinder has a longitudinally extending pressure fluid conducting passageway 33, 34 (see Figs. 2 and 5). Each passageway has a longitudinal series of ports 35, 36 respectively opening into the elliptical bore 18. The ports 35 and 36, therefore, open into the space between the cylinder and the rotor on opposite sides of the narrowest space dimension therebetween.

An exhaust for pressure fluid from the space between the rotor and the cylinder is, in the present instance, provided by means of a port 37 or series of ports located substantially in diametrically opposed relation to the line of running contact between the rotor and cylinder. The exhaust is permanently open to atmosphere and preferably the ports 37 open into an annular space 38 provided by appropriately recessing the inner wall of the casing section 11. An annular series of ports 39, through the casing section 11 and communicating with the recess 38, permits escape of pressure fluid from the casing. If desired, an annular ring 40 seated upon the casing section 11 in overlying relation to the ports 39

may be provided as a baffle for pressure fluid issuing from the ports 33 to break the force of the escaping pressure fluid and reduce the noise.

Pressure fluid for operating the motor is supplied to the present device through a passage 41 formed in the handle portion of the rear section 18. A normally closed valve 42 is interposed between the passage 41 and a continuation passage 43, the valve 42 being adapted for manipulation by such means as a finger piece 44. The passage 43 leads forwardly of the casing section 18 to a simple reversing valve mechanism, generally indicated at 45, located at the front end of the rear section in convenient position for ready manipulation by the operator.

The reversing valve mechanism 45 is best seen in Figs. 1, 4 and 6. Thus, the casing section 18 is transversely bored to receive a cylindrical member 46 constituting a valve seat. The cylindrical member is suitably secured rigidly to the rear section and has a port 47 in open communication with the passage 43. The valve seat has a pair of ports 48 and 49, each in open communication with an upwardly rising bore 50 (see Fig. 1) in the rear section 18. The bores 50 communicate with apertures 51 and 52 in the rear end plate 27, which apertures in turn communicate respectively with passageways 33 and 34 in the cylinder.

A cylindrical valve 53 is arranged to fit snugly and rotatably in the valve seat 46 and may be suitably held therein by such means as interengaging screw and washer arrangements 54, 55, at each end of the valve and valve seat. The washer in the securing arrangement 55 may conveniently be utilized to effect manipulation of the valve. To this end, a projection 56 is struck out of the washer for engagement with a recess 57 formed in the associated end face of the valve 53. A manipulable finger piece 58, extending from the washer, preferably has a shank portion engageable in an arcuate recess 59 cut in the end of the valve seat and serving to limit rotational movement of the valve.

The valve 53, opposite to the port 47 in the valve seat, has an annular groove 60. Extending longitudinally of the valve from the groove are recesses 61, 62 appropriately positioned to establish selective connection between the groove 60 and the ports 48, 49 respectively. It will be evident that by this valve arrangement, it is only necessary to move the valve into one of two positions in order to effect a delivery of pressure fluid to the space between the rotor and the cylinder on one side or the other of the line of running contact, thus effecting a driven movement of the rotor in one direction or the other. Since the exhaust ports 37 are permanently open to atmosphere, it is unnecessary in the present device to provide valve means for controlling the escape of pressure fluid from the motor.

As each vane moves past exhaust, a relatively small quantity of air will be trapped in the space between the rotor and the cylinder. It is, therefore, desirable to provide means for exhausting air from these spaces. With reference to Fig. 5, the external surface of the cylinder immediately beyond the passages 33 and 34 is longitudinally cut away, as at 63, 64. In assembly, these cut-away portions or recesses 63, 64 are open to atmosphere through the annular space 38 and ports 39 in the casing section 11. The rear end plate 27 has apertures 65, 66 (Figs. 2 and 3) communicating respectively with the recesses 63, 64 and bores (not shown) in the rear casing section 18

similar to the previously described bores 50 lead from the apertures 65, 66 respectively to ports 67, 68 (Fig. 6) in the valve seat 46. The valve 53 has recesses 69 and 70 disposed substantially in longitudinal alignment with the recesses 62 and 61, respectively. The recess 69 is dimensioned and arranged to establish communication between the pressure fluid inlet port 48 and the adjacent port 67 when the recess 62 is positioned to direct a flow of pressure fluid into the inlet passage 33 of the cylinder, and the recess 70 is similarly arranged to establish communication between the ports 49 and 68 when the recess 61 connects the inlet passage 34 with a source of pressure fluid. Hence, whenever the valve 53 is set to direct a flow of pressure fluid into one or the other of the passages 33, 34, the other passage 34 or 33 is at the same time connected with atmosphere.

In operation, and presuming that the valve 53 is set to direct a flow of pressure fluid into the passage 34, the rotor will be driven clockwise (Fig. 2). Due to the elliptical shape of the cylinder bore, the vanes will be extended to substantially their fullest effective working position within a relatively short rotational distance so that substantially the entire available energy of the pressure fluid will be transmitted to the rotor during the movement of each vane through a half-revolution. At the end of a half-revolution, the expended pressure fluid exhausts from the space behind each vane through the permanently open ports 37, which, being common to each of the intake passages 33, 34, permits the motor to be readily reversed through the sole agency of a single simple valve mechanism.

If desired, means may be provided to supplement the action of centrifugal force in moving the blades outwardly whereby positively to insure complete projection of the blades during motor operation. To this end, the rear end plate 27 has a pair of substantially diametrically opposite arcuate grooves 71, 72 formed in the rotor abutting face thereof as shown in Fig. 3. The grooves are positioned to communicate with the inner portions of the vane receiving slots 30 and are dimensioned to extend from approximately the point occupied by a vane when pressure fluid is first admitted to the space behind the vane to a point which stops just short of the position occupied by a vane when it reaches the exhaust port 37. Passages 73, 74 lead from the grooves 71, 72 respectively to the pressure fluid intake ports 51, 52. The front end plate 25 may have similar grooves 71, 72 therein, but since the front plate 25 is not provided with intake ports 51, 52, corresponding recesses are formed therein to register with and receive pressure fluid from the front ends of the pressure fluid passages 33, 34. It will be evident that when pressure fluid is delivered to either one of the passages 33, 34, for example the passage 34, a small volume of pressure fluid will be by-passed through the passage 74 to the groove 72 and thence into the slots behind the vanes. The opposite intake passage 33, being at the same time connected with atmosphere, the pressure fluid behind each vane will exhaust through the opposite groove 71 and passage 73 to permit ready retraction of the vane into the rotor.

In the present embodiment the driving gears 13 are preferably arranged as a series of planetary gears for driving the tool spindle 14. Thus, the front end of the shaft 20 is fixed to a center pinion or sun gear 75 arranged to mesh with a 75

plurality of planet gears 16 which, in turn, engage the fixed ring gear 29. The planet gears are mounted on studs 17 carried by a rotatable plate 18 rigidly connected with the spindle 14. 5 This arrangement provides a compact efficient speed reduction drive for the spindle.

From the foregoing, it will be evident that by a novel and simple construction a reversible pressure fluid actuated motor has been provided 10 which has a high operating efficiency.

I claim as my invention:

1. A reversible pressure fluid operated motor comprising, in combination, a cylinder having a bore of elliptical cross section, a rotor journaled 15 for rotation eccentrically in said bore in close proximity to the bore wall substantially on the minor axis of the ellipse, said rotor having six equidistantly spaced substantially radial slots therein, a vane slidably seated in each slot for 20 projection into wiping engagement with the bore wall during rotor movement, said ellipse being dimensioned to permit movement of said vanes outwardly substantially to their fully projected position in less than one-half of a complete revolution of said rotor, said cylinder having a permanently open exhaust port to atmosphere located 25 approximately in diametrically opposed relation to the point of close proximity of the rotor and bore wall, and having an inlet passage on each side of said point leading to the space between the rotor and bore wall, a source of pressure fluid, and a single reversible valve adapted 30 selectively to connect either of said inlet passages with said source and the other inlet passage with atmosphere.

2. A reversible pressure fluid operated motor comprising, in combination, a cylinder having a bore of elliptical cross section, a rotor eccentrically journaled in said bore on an axis located substantially on the plane of the minor axis of the ellipse, said rotor having a plurality of spaced slots therein, vanes slidably seated in said slots for movement into engagement with the bore wall during rotor movement, the shape of said ellipse being such as to permit movement of said vanes 45 outwardly substantially to their fully projected position in about one-third of a complete revolution of said rotor, said cylinder having an inlet passage leading to each side of the narrowest space between the rotor and bore wall, said cylinder having a permanently open exhaust port to atmosphere located approximately in diametrically opposed relation to said inlet passages, a source of pressure fluid, and a reversible valve 50 adapted selectively to connect either of said inlet passages with said source.

3. A reversible pressure fluid operated motor comprising, in combination, a cylinder having a bore of elliptical cross section, a rotor journaled eccentrically in said bore substantially on the minor axis of the ellipse, said rotor having spaced slots therein, a vane slidably seated in each slot for movement into engagement with the bore wall during rotor movement, said cylinder having a 60 permanently open exhaust port to atmosphere located approximately at the point of widest spacing between the rotor and bore wall and having an inlet passage at one side of the point of

narrowest spacing between the rotor and bore wall, and a source of pressure fluid adapted to be connected with said inlet passage.

4. In a device of the character described, the combination of a cylinder having a bore of oval cross section as distinguished from one of circular cross section, a rotor journaled for substantially running contact with a wall of the bore only along a line located approximately on the plane of a narrower cross dimension of the bore, 10 vanes mounted in said rotor for movement relative thereto in a substantially radial direction into engagement with the bore wall, and means providing pressure fluid passages communicating with the space between said rotor and bore wall 15 at a point substantially opposite to the line of running contact and at a point closely adjacent to said line.

5. A pressure fluid motor having, in combination, a cylinder provided with a bore, a rotor journaled for rotation in said bore with an eccentric relationship providing a line of close proximity between the rotor and bore wall, a plurality of substantially radially projectable members carried by said rotor for engagement with the bore wall during rotor movement, said bore wall being shaped to slope arcuately away from said rotor beyond said line to reach substantially its maximum spaced distance from the rotor surface at a point approximately 120° removed from said line, means for introducing pressure fluid between said wall and rotor adjacent to said line, and means providing an exhaust for fluid pressure located approximately 180° from said line of close proximity.

6. In a pressure fluid motor, the combination of a cylinder having a bore of elliptical cross section, a rotor mounted for rotation about an axis eccentric of the bore center and located substantially on the plane of the minor axis of said bore, 40 a plurality of radially movable members carried by said rotor for engagement with the bore wall, the elliptical form of the bore being such that the space between the rotor and the bore wall increases on either side of the narrowest space dimension therebetween to reach substantially the greatest space dimension approximately at the ends of the major axis of the ellipse, said space intermediate the increasing portions having generally the same greatest space dimension 45 therebetween, means for introducing pressure fluid into said space on either side of its narrowest dimension, and an open exhaust from said space diametrically opposite said narrowest dimension.

7. A pressure fluid motor having, in combination, a cylinder provided with a bore of elliptical cross section, a cylindrical rotary member having a plurality of radially movable vanes mounted therein, means for rotatably mounting said member in said bore with said member located in close proximity to the bore wall substantially on the shorter axis thereof, and means for operatively introducing and exhausting pressure fluid to and from the space between said member and bore wall, the pressure fluid exhausting means being located substantially diametrically opposite to the line of close proximity.

ERNEST H. SHAFF.
